CLAIM

The ornamental design for a combined oil sump and cooler, as shown and described.

DESCRIPTION

FIG. 1 is a perspective view of a combined oil sump and cooler showing my new design;

FIG. 2 is a top-plan view thereof;

FIG. 3 is an end-elevational view thereof;

FIG. 4 is a bottom-plan view thereof;

FIG. 5 is a side-elevational view thereof;

FIG. 6 is a perspective view of a combined oil sump and cooler showing a modified form of my new design;

FIG. 7 is a top plan view of FIG. 6;

FIG. 8 is an end elevational view of FIG. 6;

FIG. 9 is a bottom plan view of FIG. 6; and

FIG. 10 is a side elevational view of FIG. 6.

FIG. 1.

FIG._2.

FIG._3.

FIG._4.

FIG._5.

FIG. 6.

FIG. 7.

FIG. 8.

FIG. 9.

FIG. 10.
